(57) **CLAIM**

The ornamental design for a display screen with animated graphical user interface, as shown and described.

DESCRIPTION

FIG. 1 is the first image in a sequence for a display screen with animated graphical user interface showing our new design; FIG. 2 is the second image thereof; FIG. 3 is the third image thereof; FIG. 4 is the fourth image thereof; FIG. 5 is the fifth image thereof; FIG. 6 is the sixth image thereof; FIG. 7 is the seventh image thereof; FIG. 8 is the eighth image thereof; FIG. 9 is the ninth image thereof; FIG. 10 is the tenth image thereof; FIG. 11 is the eleventh image thereof; FIG. 12 is the twelfth image thereof; FIG. 13 is the thirteenth image thereof; and, FIG. 14 is the fourteenth image thereof.

The appearance of the animated graphical user interface sequentially transitions between the images shown in FIGS. 1-14. The process or period in which one image transitions to another forms no part of the claimed design. The outermost even-length broken line showing of an electronic device illustrates environmental structure and forms no part of the claimed design. The remainder of the even-length broken lines illustrate portions of the graphical user interface and form no part of the claim. The uneven-length broken line illustrates the display screen and forms no part of the claimed design.
